F. S. BLAKESLEY

SHOULDER SUPPORT FOR HAVERSACKS, ETC

Filed Aug. 18, 1920

FIG. 1.

INVENTOR.

F. S. Blakesley.

BY

ATTORNEY.

UNITED STATES PATENT OFFICE.

FRANCIS S. BLAKESLEY, OF CHICAGO, ILLINOIS.

SHOULDER SUPPORT FOR HAVERSACKS, ETC.

Application filed August 18, 1920. Serial No. 404,391.

To all whom it may concern:

Be it known that I, FRANCIS S. BLAKESLEY, a citizen of the United States, residing at Chicago, in the county of Cook and State 5 of Illinois, have invented certain new and useful Improvements in Shoulder Supports for Haversacks, Etc.; and I do hereby declare the following to be a full, clear, and exact description of the invention, such as 10 will enable others skilled in the art to which it appertains to make and use the same.

This invention has relation to certain new and useful improvements in a shoulder support for haversacks, etc., and has for its 15 primary object the provision of simple and efficient means for supporting haversacks and similar packs on the shoulders of the carrier under conditions which will not involve the discomfort and the drawing or 20 contracting and clamping effects of the straps or harness ordinarily employed for this purpose and which will allow perfect freedom of movement of the body of the carrier or wearer.

25 The invention has for a further object the provision of a shoulder support for haversacks and the like which may be readily attached to haversacks or other packs or packages without alteration in the construction 30 thereof and by means of which the pack or package may be securely and properly supported upon the shoulders of the carrier or wearer.

With the foregoing and other objects in 35 view as will appear as the description proceeds, the invention consists in the novel construction, combination and arrangement of elements as hereinafter more specifically set forth, shown in the accompanying drawings and claimed.

40 In the drawings forming a part of the present application:—

Figure 1 is a view of the support as seen when in use, applied to a haversack or similar receptacle or package.

Figure 2 is a detail perspective view showing the manner of attaching the support to the receptacle or package.

Figure 3 is a detail sectional view through 50 the fastening means for the support and showing the support in elevation and a portion of the receptacle or package in section.

Referring more in detail to the drawings 55 in which similar reference characters designate corresponding parts throughout the several views, 10 indicates a pair of arcuate

shoulder clamps or clips made of steel or similar resilient material and covered to form substantially a semi-circle or at least to an extent to assure a spring movement 60 of the terminals thereof toward each other so that when applied to the shoulders of the wearer the tendency of the extremities of the shoulder clamps or clips is to bear respectively against the back and the front 65 of the shoulder while the arched intermediate portion of each clamp or clip 10 bears upon the shoulder to carry the weight of the haversack 11 or other receptacle or package supported thereby.

In order to mount the shoulder clamps or clips 10 upon the receptacle, I have provided a rod 12 provided with turned ends 13 and upon the main portion of which rod 12 are mounted the rolled ends 14 of the 75 shoulder clamps or clips 10 adjacent the opposite ends 13 of said rod 12. This rod 12 is covered by a retaining strip 15 of any suitable material such as thick leather, metal or the like. The strip 15 has suitable openings 80 16 to accommodate the rolled ends 14 of the shoulder clamps or clips 10 and the strip 15 is secured in position preferably by a row of stitching 17 or the like around its edge portion. The rod 12 is also preferably 85 held in position by a row of stitching 18 or the like through the strip 15 and the portion of the receptacle 11 upon which the strip 15 is mounted, the row of stitching 18 extending around the side and ends of 90 the rod 12, as indicated by dotted lines in Figure 2 of the drawing. It will be understood from the foregoing paragraphs taken in connection with the accompanying drawings forming a part of this application that 95 the shoulder clamps or clips 10 may be placed any suitable distance apart so as to rest comfortably upon the shoulders of the wearer or carrier. It will also be understood that the clamps or clips 10 are preferably 100 heavily padded as indicated at 19 for the comfort of the wearer or carrier.

While the preferred embodiment of the invention has been shown and described, it will be understood that minor changes in 105 the details of construction and arrangement of parts may be resorted to within the scope of what is claimed without departing from the spirit of the invention.

What is claimed is:—

1. A haversack consisting of a containing body, an anchor disposed on the body, a

flexible securing element fastened to the body and over said anchor, said element having a slot therethrough, a substantially arcuate securing member through which said anchor passes and extending through said slot, whereby said securing member is mounted against displacement in a direction longitudinally of the anchor member, and said securing member being pivoted on said anchoring member.

2. A suspending means of the class described having a suspending member, an anchor from which said suspending member extends, a flexible securing element for dis-

position over said anchor and attachable to an article to fasten the anchor in place, said element having a slot therethrough, and said suspending member extending through said slot and being maintained by the walls thereof against displacement in a direction longitudinally of the anchor member.

In testimony whereof I affix my signature in presence of two witnesses.

FRANCIS S. BLAKESLEY.
